Italian Search Report issued in Application No. UA20164439, dated Feb. 8, 2017.

Primary Examiner — Cynthia R Underwood

(74) Attorney, Agent, or Firm — Young & Thompson

(57) **CLAIM**

The ornamental design for a screw and nut, as shown and described.

DESCRIPTION

FIG. 1 discloses a top perspective view of a screw and nut of my new design;

FIG. 2 discloses an elevational view thereof;

FIG. 3 discloses a top plan view thereof; and,

FIG. 4 discloses a bottom plan view thereof.

The portions of the design shown in broken lines show unclaimed subject matter.
